GARBAGE CAN STAND

Casimer Kilian, Dunkirk, N. Y.

Application June 9, 1950, Serial No. 167,075

2 Claims. (Cl. 248—153)

1

This invention relates to holders for retaining garbage cans and other exposed receptacles outdoors, and more particularly to an improved stand for supporting a garbage can or similar receptacle in upright position and off the ground.

A main object of the invention is to provide a novel and improved stand for a garbage can or similar receptacle, said stand being very simple in construction, being easy to mount in the ground, and providing a means of supporting the garbage can or similar receptacle out of contact with the ground and in a secure upright position, whereby the contents of the receptacle will not be accidentally spilled by winds or by animals and whereby rusting of the bottom of the receptacle is prevented.

A further object of the invention is to provide an improved supporting stand for a garbage can or similar receptacle, said stand being very inexpensive to manufacture, being rugged in construction, being simple to install, and enabling the garbage can or other receptacle to be readily removed for emptying thereof.

Further objects and advantages of the invention will become apparent from the following description and claims, and from the accompanying drawings, wherein:

Figure 1 is a perspective view of an improved garbage can stand constructed in accordance with the present invention, showing the ground engaging stop pads employed with the legs of the stand.

Figure 2 is a side elevational view showing the stand of Figure 1 mounted in the ground and supporting a garbage can therein.

Figure 3 is an enlarged detail view in vertical cross section showing the connection of the top circular ring to one of the legs of the stand, showing the connection of the lower ring to the lower portion of said leg, and showing the triangular stop lug on the leg cooperating with the ground engaging support pad to limit penetration of the leg into the ground.

Figure 4 is a perspective view of the garbage can supporting stand of Figure 1 but showing the ground engaging legs bent outwardly.

Referring to the drawings, the stand is generally designated at 11 and comprises four equally spaced upstanding legs 12 made of metal rods and pointed at their lower ends as shown at 13. Welded to the upper end portions of the legs 12 is a circular metal ring 14 and welded to the intermediate portions of said legs is a second metal ring 15, slightly smaller in diameter than the top ring 14. The legs 12 therefore converge

2

downwardly, as shown in Figure 1. Secured to the lower ring 15 at right angles to each other are the respective depending U-shaped cross bars 16, 16 which define a supporting receptacle for holding a garbage can positioned as shown in Figure 2. The garbage can is designated at 17, and as shown in Figure 2 the intermediate portions of the U-shaped cross bars 16, 16 are slightly bowed upwardly at their middle portions, whereby the garbage can 17 is supported substantially at the center of its base allowing free passage of air around substantially the entire area of its bottom surface. Secured to the lower portions of the legs 12, as by welding or the like, are inwardly directed triangular lugs 18, and designated at 19 are apertured metal pads which may be positioned on the lower portions of the legs 12 in the manner shown in Figure 2 and which are engaged by the lugs 18 to limit downward penetration of the legs 12 into the ground.

As shown in Figure 2, the stand 11 may be mounted in position by driving the pointed ends 13 of the legs 12 into the ground with the pads 19 engaged on the legs, the stand being properly positioned when the lugs 18 engage the pads 19, as shown. Alternatively, the lower portions of the legs 12 may be bent slightly outwardly, as shown in Figure 4, at 20, whereby the lower portions of said legs diverge downwardly instead of being convergent downwardly as in Figure 2. The pads 19 are employed with the legs 12 of Figure 4 in the same manner as in Figure 2.

It will be apparent that when the stand is mounted in the ground, a garbage can, such as the can 17 of Figure 2, will be supported with its bottom portion out of contact with the ground and will be held against tipping or upsetting by the engagement of the upper ring 14 with the upper portion of the can body. It will also be apparent that the can may be readily removed from the support by merely lifting the can upwardly out of the support. By the use of the improved support the garbage can is protected against spilling by winds and against upsetting by animals, and the bottom of the garbage can is protected against contact with the ground, whereby the life of the can is greatly increased.

The connections of the various elements of the stand to each other are preferably made by welding, and the various rod elements and ring elements are preferably made of galvanized rod stock or of other suitable corrosion resistant metal.

While certain specific embodiments of an improved garbage can support have been disclosed

in the foregoing description, it will be understood that various modifications within the spirit of the invention may occur to those skilled in the art. Therefore, it is intended that no limitations be placed on the invention except as defined by the scope of the appended claims.

What is claimed is:

1. A support for an outdoor receptacle comprising a horizontally disposed ring, a plurality of upstanding legs arranged exteriorly of and in spaced relation about said ring and each having the upper end secured to the adjacent portion of said ring, the lower end of each of said legs being provided with a point for penetration into a ground surface, a second horizontally disposed ring disposed interiorly of said legs intermediate the upper and lower ends of the latter and fixedly secured to the adjacent portion of said legs, a pair of bar elements arranged in crisscross relation positioned intermediate said legs and below said second ring and having their ends dependingly secured to said second ring, a fixed lug projecting from each leg intermediate the pointed lower end and said second ring, said lugs being horizontally aligned, and apertured stop plates slidably engaged on the portions of said legs below said lugs for limiting penetration of the pointed ends of the legs into the ground.

2. A support for an outdoor receptacle comprising a horizontally disposed ring, a plurality of upstanding legs arranged exteriorly of and in spaced relation about said ring and each having

the upper end secured to the adjacent portion of said ring, the lower end of each of said legs being provided with a point for penetration into a ground surface, a second horizontally disposed ring disposed interiorly of said legs intermediate the upper and lower ends of the latter and fixedly secured to the adjacent portions of said legs, a pair of U-shaped bars arranged in crisscross relation positioned intermediate said legs and below said ring and having their ends secured to said second ring, a fixed triangular shaped lug projecting from each leg intermediate the pointed lower end and said piston ring, said lugs being horizontally aligned, and apertured stop plates slidably engaged on the portions of said legs below said lugs and being engageable with said lugs for limiting penetration of the pointed ends of the lugs into the ground.

CASIMER KILIAN.
